UNITED STATES PATENT OFFICE.

NANCY J. GRAHAM, OF JACKSON, OHIO.

PLAITING-MACHINE.

SPECIFICATION forming part of Letters Patent No. 237,858, dated February 15, 1881.

Application filed December 26, 1878.

To all whom it may concern:

Be it known that I, NANCY JANE GRAHAM, of Jackson, in the county of Jackson and State of Ohio, have invented certain new and useful 5 Improvements in Plaiting-Machines; and I do hereby declare that the following is a full, clear, and exact description of the same, reference being had to the accompanying drawings, forming part of this specification, in 10 which—

Figure 1 is a vertical longitudinal sectional view of my improved plaiting-machine, and Fig. 2 is a plan view of the same, the goods being shown in place upon the needles in both 15 figures.

The invention has relation to plaiting-machines; and it consists in the improvements in the construction of the same, hereinafter fully described, and particularly pointed out in the 20 claim.

The objects to be attained by the construction hereinafter set forth are twofold—viz., to permit the goods to be pressed upon the needles and dried around the same without coming in contact with the bed-plate of the machine; and, secondly, to permit a greater variety of plaiting to be made upon the machine than has been heretofore attainable.

Referring by letter to the accompanying 30 drawings, F designates the bed-plate of the machine, to the sides of which are rigidly secured perforated vertical side plates, G G. These side plates are provided with three courses of perforations, *a b c*, arranged one 35 above the other and diminishing in size from below upward. Needles H H' H², corresponding in size to the several courses of perfora-

tions *a b c*, are employed in the usual manner to form the box-plaitings in the material. The lower and largest course of perforations are 40 located a short distance above the bed-plate, in order that the plaiting may be pressed upon the needles without coming in contact with the bed-plate, and, after having been pressed, the plaiting or material is dried upon the needles before being stitched.

A, B, C, D, and E designate different forms of box-plaits.

The needles fit the perforations snugly, and cannot become displaced during the operation 50 of forming the plaits; consequently the work can be accurately performed.

The several courses of perforations, varying in size, permit of forming plaits in the heaviest or the lightest materials.

In some instances, where the goods are difficult to plait, an extra board or bed-plate may be placed upon the bed-plate F and under the needles, so that the plaits may be pressed; but with all ordinary materials the pressing 60 is performed upon the needles.

Having thus fully described my invention, what I claim as new, and desire to secure by Letters Patent, is—

In a plaiting-machine, the combination, with 65 the bed-plate F and the needles H H' H², varying in size, of the side pieces, G G, provided with the courses of perforations *a b c*, arranged one above the other and varying in size, as do the needles, substantially as set forth.

NANCY J. GRAHAM.
